UNITED STATES PATENT OFFICE.

WILLIAM H. DAYTON, OF TORRINGTON, CONNECTICUT, ASSIGNOR TO THE EXCELSIOR NEEDLE COMPANY, OF SAME PLACE.

MACHINE FOR GROOVING SEWING-MACHINE NEEDLES.

SPECIFICATION forming part of Letters Patent No. 351,900, dated November 2, 1886.

Application filed March 24, 1886. Serial No. 196,314. (No model.)

To all whom it may concern:

Be it known that I, WILLIAM H. DAYTON, of Torrington, in the county of Litchfield and State of Connecticut, have invented an Improvement in Machines for Grooving Sewing-Machine Needles, of which the following is a specification.

Letters Patent No. 245,356, granted to the Excelsior Needle Company, as my assignees, 10 represents a machine for grooving sewing-machine needles, and so far as the cutters and the mode of operating the same and the devices for clamping the needle the parts of my present invention correspond to those in said 15 patent, and similar letters of reference are placed thereon; hence these parts do not need to be further described, except to show their connection with the present improvements.

My present improvements relate to devices 20 for supplying the needle-blanks automatically into the holding-dies, and also to means for supporting the shank of the needle at the commencement of the grooving operation, and to means for removing the needle from the holding-jaws after it has been grooved.

In the drawings, Figure 1 is a vertical longitudinal section of the machine. Fig. 2 is a plan. Fig. 3 is an inverted plan; and Fig. 4 a cross-section at the line $x-x$, Fig. 1. Fig. 5 30 is a separate view showing the cam, pin, and secondary lever, which actuate the clamping-jaw; and Fig. 6 is a separate view of the cam for actuating the holding and delivery fingers.

The bed A of the machine receives upon it 35 the slides a, in which the moving bed b is supported, and upon this are the jaws d d', that are grooved upon their adjacent surfaces for the reception of the needle-blank, and k k' are the cutters for grooving the needles. The bed 40 b is reciprocated by the cam D on the main shaft E, and at F is the driving-shaft, with a worm-pinion, G, meshing with the wheel H upon the said main shaft E. The bevel-gear I upon the driving-shaft F gives motion to 45 the bevel-gear K and its shaft, and to the worm-pinion L and worm-wheel M, upon the shaft 12, whereby I am enabled to actuate the machine by power, so that the shaft 12, wheels r, and other parts that operate to move the 50 cutters up to their work may act in harmony

with the reciprocating movement given to the bed b, and the jaws d d', carried by the same.

The jaw d' is at the end of a lever, d², pivoted at d³, and upon the shaft 12 is a cam, e³, that acts upon a vertical pin, e⁵, and this rests 55 upon one end of the secondary lever e⁶, that is pivoted at e⁴ on the bed b, and the other end of this secondary lever e⁶ is beneath the adjusting-screw e⁷, that passes through the lever d², so that when the cam e³, acting upon the pin 60 e⁵, presses upon the secondary lever e⁶, the rear end is raised and the lever d² moved so as to press the grooved jaw d' down upon the needle-blank and hold the same. When the cam e³ releases this lever e⁶, the spring e⁸ opens the 65 jaws. The cam e³ is so made as to cause the lever d² and its jaw d' to grasp the needle-blank after the same has been properly placed between the jaws and before the cutters k k' are moved up and the grooving commenced.

One of the principal features of my present invention relates to the means for supplying the needles. I employ a feed-wheel, O, upon a vertical stud, O', that is upon the sliding bed P, and there are ways or slides P' upon the bed A to sustain the sliding bed P. This feed-wheel O is made with radial grooves in the flat upper surface, and over each of these radial grooves is a spring-finger, p, the end of which is rounding or bent up, to facilitate the insertion of the shank of the sewing-machine needle-blanks into such grooves. The feed-wheel 75 O is recessed in its upper surface, and the grooves are in the upper edge of the annular rim of the wheel, and within the said recess is 80 the flat ring or disk O², the edge of which forms a stop for the shanks of the needle-blanks.

The attendant places the shanks of the needle-blanks into the radial grooves in the feed-wheel, and the sliding bed P is moved forward at the proper time by the cam Q on the main shaft E, said cam acting upon the roller q, beneath the bed P, and the needle-blank that is in line with the jaws d d' is passed into the 90 same, and the jaws are closed to hold the needle-blank, as before described, and the bed P and feed-wheel are drawn back, leaving the needle in its proper position for being grooved.

In order to revolve the feed-wheel O pro- 95

gressively and to hold the same firmly while being moved toward and from the jaws d d' , I make use of a pawl, R, pivoted at R' upon a link, R², the other end of which link is secured by the screw r⁶ to a projection from the bed P. The end of the pawl R' is adapted to enter successively within the vertical notches upon the periphery of the feed-wheel O, and there is an incline, S, that acts upon a roller, 10 s', upon the under side of the link R², and there is a guide-bar, s², with an inclined end corresponding to the angle of the incline S. The distance between the incline S and the inclined end of the guide-bar s² corresponds to the diameter of the roller s'. The 15 operation of this part is that as the bed P is reciprocated and the link R² and pawl R' are moved back and forth the incline S swings the link and pawl to cause said pawl to slide over the periphery of the feed-wheel and drop into the next notch, and when the bed P is moved in the other direction the inclined end of the guide s² causes the link R² and pawl to turn the feed-wheel around one division and bring another needle-blank into line with the jaws d d', and the straight side of the guide s² being parallel with the central line of the machine, the feed-wheel is not turned while being moved after the roller s' passes upon the straight portion of the guide s².

After the needle-blank has been introduced between the jaws d d' and clamped by the same it is important that the shank of the needle-blank be steadied during the commencement of the operation of the cutters, because only one cutter acts upon one side of the needle-blanks at the commencement of the grooving, and the needle-blank is liable to be bent by the pressure of the cutter against the side 35 of the blank at the junction of the needle with the shank, or the groove to be made rough by the "chattering" under the action of the cutter. To obviate this difficulty and also to remove the needle-blank when it has been 40 grooved, I make use of holding and delivery fingers T T', to which a compound movement is given by the devices next described.

Upon the bed A is a tubular stud, U, and around this is a cam, U', the cam-surface of 45 which is upon the upper end, and this tubular cam can be raised or lowered upon the stud to adjust the same, and it is held by a clamping-screw. Through the tubular stud is a tubular stock, V, at the upper end of which is a jaw, V', that rests upon the top of the tubular stud U. Within the jaw V' is received the back end of the holding-finger T, the finger being attached to the jaw by pivots, so that the finger can be swung up and down between the sides 55 of the jaw. The finger T' is pivoted at t to the jaw T, and there is a spring, t', that acts to raise the finger T' and open the fingers. Passing through the tubular stock V is a rod, Y, the upper end of which is beneath the rear 60 end of the finger T'. Below the bottom end of this rod Y is a lever, Y', pivoted at Y', and having an adjusting-screw, y, to act di-

rectly upon the bottom end of this rod Y, and there is a cam, Y², upon the driving-shaft E, that acts against a roller, Y⁴, upon the lever Y'. The shape of this cam Y² is such that it will raise the rod Y and close the fingers T T' at the proper time, or release the parts and allow said fingers to be opened by the spring t'.

At the bottom of the tubular stock V is a 75 pinion, V², and V³ is a toothed sector upon a pivot, V⁴, and there is a roller or stud, V⁵, against which cams V⁶ V⁷ upon the driving-shaft act.

The cams being properly shaped and timed, 80 the operations are as follows: The cam V⁶, acting through the toothed sector V³, partially revolves the pinion V² and tubular stock V and swings the fingers T T' toward the folding jaws d d'. At the commencement of the movement the fingers are above the feed-wheel O, and are held up by the cam U'. As the fingers swing clear of the feed-wheel O, they are lowered at their outer ends by sliding down the cam U', and at this time the open ends of the fingers 90 are at the level of the shank of the needle and swing along horizontally, passing above and below the said shank. The cam Y³ now acts, and by the lever Y' and rod Y closes the fingers, grasping and holding the shank 95 of the needle while the cutter k is pressed up and commences to groove the needle at one side. As soon as the cutter has cut in the full depth of the groove on one side the bed b commences to move endwise. At this 100 moment the cam Y³ ceases to act, and the fingers T T' are loose, and they swing back as the ends of the jaws d d' move along against them. When the needle has been entirely grooved and the jaw d' liberated, a projection of 105 the cam Y³ again acts upon the lever Y' and rod Y to close the fingers T T' and grasp the shank of the grooved needle-blank. The cam V⁷ now acts, and by the toothed sector V³ and pinion V² turns the tubular stock V, swinging 110 the fingers T T' around and drawing out the needle-blank, and in this movement the portion of the finger T that rests upon the tubular cam U' runs up the inclined surface of said cam, and the fingers are raised so as to carry the 115 needle-blank up above the feed-wheel O and swing the same entirely clear therefrom. The cam Y³ now ceases to act, the spring t' opens the fingers, the needle-blank drops away from the same, and the operations are repeated. 120

I claim as my invention—

1. The combination, with the jaws for holding the needle-blank, and the cutters and mechanism for grooving the same, of a feed-wheel having radial notches and spring-fingers for holding the shanks of the needle-blanks, and a stud and sliding bed for sustaining and moving the feed-wheel, substantially as specified.

2. The combination, with the jaws for holding the needle-blank, and the cutters for grooving the same, of the secondary lever e⁶, shaft 12, cam e⁷, and adjusting-screws, substantially as set forth.

3. The combination, with the clamping-

jaws for holding the needle-blank, and the cutters for grooving the same, of the driving shaft F, bevel-gearing, worm-pinions, and wheels, the shaft 12, and mechanism for controlling the action of the cutters and the main shaft, the bed for supporting the holding-jaws, and a cam upon the main shaft for moving the bed and jaws endwise, substantially as specified.

10 4. The combination, with the holding-jaws and grooving-cutter, of a feed-wheel for supplying the needle-blanks, fingers for holding the shank of the needle-blank at the commencement of the grooving operation, and for withdrawing and delivering the needle-blank, and the mechanism, substantially as specified, for giving motion to the respective parts.

20 5. The combination, with the feed-wheel, of a supporting-stud, a sliding bed, a pawl, a link, a roller connected with the pawl, an incline for moving the pawl and turning the feed-wheel, and a guide parallel with the axis of the machine for allowing an endwise movement to be given to the sliding bed to pass the 25 needle-blank into the holding-jaws without turning the feed-wheel, substantially as set forth.

6. The combination, with the holding and delivery fingers T T', of a tubular stock to 30 which such fingers are connected, a rod pass-

ing through the tubular stock for closing the fingers, and a cam and lever to act upon such rod, substantially as set forth.

7. The combination, with the holding and delivery fingers, of a cam and mechanism to 35 close such fingers, a stock for supporting such fingers, a pinion on the stock, and a toothed sector and cams for turning the stock and swinging the fingers laterally, substantially as set forth.

40 8. The combination, with the holding and delivery fingers, of the tubular stock and jaw, the tubular stud for supporting the same, the tubular cam around the stud for raising and lowering the fingers, and mechanism, substantially as specified, for opening, closing, and swinging the fingers, as set forth.

45 9. The feed-wheel O, having a rim around its edge and radial grooves in the same, in combination with the spring-fingers at the grooves for holding the needle-blanks and the separate disk or flat rim within the feed-wheel, forming an abutment for the ends of the needle-blanks, substantially as set forth.

Signed by me this 10th day of March, A. D. 55
1886.

WILLIAM H. DAYTON.
